PATENTED AUG. 20, 1835.

H. HUNSICKER & J. KRAUSS.
BRICK PRESS.

Fig. 1.

Fig. 2.

Henry Scammon and Joel Krauss, of Northampton Borough, Penn.

Letters Patent

The Schedule referred to in these Letters Patent and making part of the same containing a description in the words of the said Henry Scammon and Joel Krauss themselves of their improvement in a machine for pressing and finishing Bricks.

To all to whom these presents shall come, - Be it known that Henry Scammon and Joel Krauss, of the Borough of Northampton in the County of Lehigh and State of Pennsylvania have invented a new and useful machine for pressing and finishing Bricks and that the following is a full and exact description of the same as invented by us. - In the annexed drawing fig. 1. is a vertical longitudinal section of the machine through the centre at A. showing one of the side pieces of which there are two, about 4 feet long 13 inches broad and placed about 16 inches inside apart. They constitute the foundation of the machine. have cross ties at B.B. and are placed upon brick wheels C.C. so as to render the machine portable. D.D. are a pair of cast iron brick moulds, cast in one piece the side E. which connects them together being cast with a projection or flange E' on the inner side that projects internally over the bottom edge of the moulds & externally forms a shoulder that fits on the top of the two iron ways or bars G. secured on the tops of the side pieces on which the moulds are made to slide so as to bring them alternately under the operation of the pressing lever herea few mentioned, for the purpose of diminishing the friction to stop the moulds at the proper points of the rail. small friction rollers I. I. are set into the bottom of the moulds on each side, which drop into the depressions or notches b.b. so that the moulds may not roll on the rail while the brick is pressing. G.G. represent the covers of the moulds each having a follow C. that enters the mould a short distance, and on the top a friction roller d. that bears on a strong pin or shaft e. passing through bearing f. cast solid with the cover, which roller which secures the pressure from the pressing lever. g is a central shaft which bears in suitable boxes placed on the middle of the top edge of the connecting sides of the moulds. I', h.h. are two fixed arms of which there are two to each mould cover, which project from said shaft making an angle of about 120° with each other and are secured to the tops of the covers by screws or rivets. The object of which arrangement is to cause either cover to rise when the opposite one is depressed by the lever. H.H. are the pistons, the feet J.J. of which pass through the guides

tured to the bottom of the moulds by brass rods m. m. and screws and nuts m. m. by which they can be regulated. a rectangular slot or arm p. projects from each piston foot to which is connected a chain that passes over a fixed pulley t. on the centre shaft, the effect of which arrangement is that these pistons will rise or fall as their respective cones are raised or depressed. the length of the chain q. is such that the piston is not supported thereby whilst the brick is passing but bears with its under side on the adjusting screw r. r. passed up through the flange t. a screw or pin v. being inserted in the top of the pulley t. to prevent the chain from slipping. to support the pressing lever which is of wrought iron 3 or 4 feet long but may be of a length proportionable to the required pressure, it is attached to a double eccentric or cam l. cast with a strong shaft m. that bears in appropriate boxes s. s. secured to the tops of substantial iron uprights n. let into and secured to the outside of the side pieces and which for greater firmness are branched and secured near the upper edges of said pieces. from one end of the shaft m. it deviates as seen in fig 2 a straight arm o. with a friction roller t. in the end of it that works in a notch x. formed by 2 pegs ^{cast} cast solid on the outside of the connecting portion t. of the moulds the effect of which is to slide the moulds back and forth by the motion of the lever bringing them alternately under its pressure. to meet the pressure of the lever at the proper and useful point a cap box p. is secured to the top of the side pieces at each end of the machine having a long screw v. in the centre with a broad head which may be elevated or depressed. Two stops y. y. being attached to the lever the ends of which strike on the heads of the screws v. and check the further descent of the lever.

Operation. the brick being moulded and prepared for passing in the common way as brick is placed in the piston of the open mould. the lever t. is then drawn towards that mould and by the operation of the arm o. the mould and brick is brought under the cam shaft m. by the pressure first operation of the cam l. and arm o. the cover of the mould containing the brick having been closed, and its piston depressed so as to bear on the screw v. v. whilst the cover of the opposite mould by the same operation has been raised and its piston elevated on the lever t. being still further depressed the arm o. disengages immediately from the notch x leaving the moulds at rest and the cam commences to press on the friction roller t. and continue to operate more and more powerfully until the stop y. strikes the head of the screw v. and the pressure is finished. a second brick is now placed in the opposite

and the base K being caused onwards that side of the machine operates on it in a similar manner to that just described at the same time raising the cover and piston of the first mould and discharging the first brick which is to be replaced whilst the process of the second is completing and the operation is thus repeated with greater economy of time and labour than ⁱⁿ any machine hitherto used although we have described an arm O whereby to shift or slide the moulds we prefer to effect the same thing by a simple lever conducted at the place where the arm O is working on a cogged slide at the outside of the moulds through which the arm for its simplicity. but what we do claim in our machine as principles for which we ask Letters Patent is the plan of a double pressure v. connected cross of the double moulds and the friction rollers which are let into the bottoms of the moulds, and the arms or cog wheels on the cam shaft by the simultaneous operation of all which through the motion of the pressing lever on cam shaft along the brick, are pressed and discharged in the moulds brought under the pressure of the cam in regular alternation. We claim also the substantial iron uprights where the cam shaft rests on. In testimony that the foregoing is a true specification ^{of our invention} we have hereunto set our hands this 28 day of July 1835. The above machine is to be made to press the bricks edgeways, as well as flat if required
